UNITED STATES PATENT OFFICE.

WILLIAM A. FARISH, OF NORFOLK, VIRGINIA, ASSIGNOR TO OWL HEADLIGHT SCREEN CO., INC., OF NORFOLK, VIRGINIA, A CORPORATION OF VIRGINIA.

HEADLIGHT SCREEN.

Application filed November 7, 1922. Serial No. 599,567.

To all whom it may concern:

Be it known that I, WILLIAM A. FARISH, a citizen of the United States, residing at Norfolk, in the county of Norfolk and State 5 of Virginia, have invented certain new and useful Improvements in Headlight Screens, of which the following is a specification.

This invention relates to screens for automobile headlights, and has as one of its primary objects to provide a screen which will 10 permit the passage of light rays in a manner to intensely and most effectually illuminate the road surface without any liability, however, of blinding anyone standing or 15 traveling in the path of the rays.

Another object of the invention is to provide a headlight screen which may be conveniently and economically manufactured and which will be substantial and capable 20 of installation by any inexperienced person.

The screen embodying the invention is of the louver type and another important object of the invention is to provide novel means for securing the slats of the louver 25 in place within the annular member comprising the frame of the screen so that the slats will be securely held against displacement and prevented from becoming distorted or loosened.

Another important object of the invention 30 is to disclose a method of finishing a headlight screen of the louver type so that the maximum benefit will be obtained from the source of illumination without any blinding 35 effect being produced.

A further object of the invention is to construct the slats in a novel manner contemplated to effectually reinforce them so as to prevent distortion and likewise render 40 them so rigid as to substantially eliminate vibration under travel conditions.

In the accompanying drawings:

Figure 1 is a perspective view of an automobile headlight equipped with the screen 45 embodying the invention;

Fig. 2 is a perspective view of the screen removed looking at the face thereof;

Fig. 3 is a vertical front to rear sectional view through the screen and the headlight 50 within which it is mounted;

Fig. 4 is a view similar to Fig. 3 illustrating one manner in which the screen is anchored against downward displacement;

Fig. 5 is a similar view illustrating an-

other manner in which the screen may be 55 anchored;

Fig. 6 is a vertical transverse sectional view through the louver portion of the screen and looking at the rear face thereof;

Fig. 7 is a fragmentary sectional perspective view illustrating a modified manner in which the louver slats may be secured in place.

In the drawings the numeral 1 indicates the shell or casing of an ordinary automobile headlight and the numeral 2 the usual conoidal reflector which is mounted therein and is provided with the usual flange extending circumferentially of its open front and indicated by the numeral 3. This 70 flange, as is usual, is provided in its face with the usual annular channel 4 in which is arranged a packing 5 and against which packing the lens 6 is ordinarily placed and held by the usual removable rim 7 which 75 is fitted onto the front of the shell 1. The headlight bulb is indicated by the numeral 8 and is arranged in the usual position within the reflector 3.

The screen embodying the invention is 80 indicated in general by the numeral 9 and comprises an annular frame member 10 preferably formed from sheet metal of a suitable gage, although other material might be employed for the purpose. The opening 85 defined by the frame 9 is indicated by the numeral 11 and is left uncovered throughout approximately its lower half, the louver device occupying the upper portion of said opening. At the extreme top of the frame 90 10 the opening 11 has its wall extended chordal to the frame as indicated by the numeral 12, and the louver slats, which are indicated in general by the numeral 13, are supported within the frame parallel to the 95 said edge 12 and to each other. Each of the slats 13 comprises a strip 14 of sheet metal or any other material found suitable for the purpose, and this strip has its end edges cut diagonally or on curved lines, 100 either as desired, and converging toward the edge which is located at the rear when the screen is in place, these said end edges being indicated by the numeral 15 and being formed in the manner stated so as to conform more or less closely to the contour of the inner surface of the reflector 2. The strips 14 are provided each with a longi-

100

95

105

tudinally extending corrugation or crimp indicated by the numeral 16 and this crimp or corrugation serves to stiffen and reinforce the slat so as to prevent its distortion and render it rigid and substantial. Likewise the corrugation serves to prevent undue vibration of the slat under conditions of travel.

In preparing the frame 10 to mount the slats comprising the louver, portions of the frame at the opposite sides of the upper half of the opening 11 are struck in and constitute rearwardly converging seating flanges 17. The said flanges 17 are corrugated at suitable intervals throughout their lengths and each of these corrugations, indicated by the numeral 18, provides a shoulder 19 upon which the end edge of the respective slat to be supported is disposed, the slat being soldered at its end to the said shoulder and in the angle formed by the corrugation. The corrugations 18 are extended upwardly and rearwardly at angles to the plane of the frame 10, and consequently the slats 13 are correspondingly inclined although they all occupy planes parallel to one another.

In installing the screen, it is disposed between the packing 5 and the rear side of the headlight lens 6, with the louver slats 13 projecting rearwardly and upwardly from the plane of the frame of the screen and the plane of the lens. With the screen thus mounted, light rays will be prevented from passing in an upward direction from the reflector and through the lens, and, on the other hand, will be directed at the proper angle onto the road surface, the angle of inclination of the slats being such as to deflect the rays reflected from the upper and inner portions of the reflecting surface downwardly onto the road surface at the proper angle. It will be evident that the light rays falling upon the faces of the flanges 17 will be reflected so as to be thrown at opposite sides of the roadway.

As a means for anchoring the screen and preventing its downward displacement or displacement in any other direction with relation to the headlight lens, the frame 10 of the screen is provided at its upper side at spaced points with upwardly radially projecting ears 20 which are adapted to be bent over the rim of the lens, as illustrated in Fig. 4 of the drawings and as indicated by the numeral 21, or to be bent rearwardly and over the portion of the flange 3 of the reflector which houses the packing 5 and as

indicated by the numeral 22 in Fig. 5 of the drawings.

The screen is, as previously stated, preferably of sheet metal, and there is applied to all portions of its surface, and, more especially the surfaces of the louver slats, a coating 23 of paint of a flat white color, or a coating of some other character may be employed to provide a reflecting surface. It has been found by actual test that by employing paint of this color and kind, the most satisfactory results may be obtained.

If desired, the ends of the slats 13, instead of being soldered in place or brazed, or spot welded, as would be the case where they are seated in the angles formed by the corrugations 18 as previously described, may be retained between crimps or more definitely formed corrugations 24 as shown in Fig. 7 of the drawings, and by the use of a punch or the like, an indentation 25 may be made in one of the pairs of corrugations confining the edge of each strip for the purpose of more securely anchoring the strip.

Having thus described the invention, what is claimed as new is:

1. A headlight screen comprising a frame having spaced corrugated flanges, and louver slats seated and supported at their ends in the valleys of the corrugations in said flanges.

2. A headlight screen comprising a frame having spaced corrugated flanges extending at an angle of inclination to the plane of the frame, and louver slats seated and supported at their ends in the valleys of the corrugations in said flanges.

3. A headlight screen comprising an annular frame having opposite side portions turned rearwardly from its plane to provide supporting flanges, and a plurality of louver slats supported by said flanges and extending in parallelism between the same, each of said slats comprising a strip of sheet material provided with a longitudinal reinforcement.

4. A headlight screen comprising an annular frame having opposite side portions turned rearwardly from its plane to provide supporting flanges, and a plurality of louver slats supported by said flanges and extending in parallelism between the same, each of said slats comprising a strip of sheet material provided with a longitudinal corrugation.

In testimony whereof I affix my signature.

WILLIAM A. FARISH.
